CLAIM

The ornamental design for an air fryer as shown and described.

DESCRIPTION

FIG. 1 is a top view of the air fryer according to the invention.

FIG. 2 is a front view of the air fryer.

FIG. 3 is a rear view of the air fryer.

FIG. 4 is a left side plan view of the air fryer.

FIG. 5 is a right side plan view of the air fryer.

FIG. 6 is a perspective view of the air fryer according to the invention, showing the base and side of the air fryer

FIG. 7 is a perspective view of the air fryer according to the invention, showing the top and side of the air fryer; and,

FIG. 8 is a bottom view of the air fryer.

The broken lines are for the purpose of illustrating the environment of the article only and form no part of the claimed design.
